COMBINED RAIL ANCHOR AND TIE PLATE

Filed Sept. 24, 1925

Inventor

W. P. Hesterly.

By *W. P. Hesterly* Attorney

UNITED STATES PATENT OFFICE.

WILLIAM P. HESTERLY, OF LUFKIN, TEXAS.

COMBINED RAIL ANCHOR AND TIE PLATE.

Application filed September 24, 1925. Serial No. 58,398.

My invention relates to tie plates, and has for one of its objects to improve and simplify the general construction of devices of this character and to provide one which, 5 in addition to performing the usual functions of a tie plate, will serve as a rail anchor.

The foregoing and other objects are attained by the construction, combination and 10 arrangement of parts hereinafter fully described and claimed, and illustrated in the accompanying drawing, wherein:

Figure 1 is a view illustrating the application of the tie plate to a railway rail, and 15 Figure 2 is a detail perspective view of the tie plate.

Corresponding and like parts are referred to in the following description and designated in both views of the drawing by similar reference numerals.

The tie plate 1, which is preferably made of tempered steel is provided at its upper side with a longitudinal rib 2 and resilient hooks 3. The rib 2 is located adjacent a 25 side edge of the plate 1, and the hooks 3 are located at the corners of the plate adjacent the other side edge thereof. The hooks 3 overlie the plate 1, and their free or inner terminals are curved upwardly as shown 30 at 4. The hooks 3 may be formed by slotting the plate 1 adjacent and parallel to the end edges thereof, and by then bending upwardly and inwardly those portions located between the slots and end edges of the plate. 35 The plate 1 is provided near the rib 2 with spike receiving openings 5 and intermediate the hooks 3 with a spiked receiving opening 6. The opening 6 extends transversely of the plate 1 and is longer than the corresponding dimension of the spike to be 40 inserted therethrough to adapt the device for application to different weight rails.

In practice, the tie plate is adapted to be applied to a rail 7 in the manner illustrated 45 in Figure 1. The rib 2 contacts with an edge of the base of the rail and the hooks 3 overlie and contact with the base adjacent the other edge thereof. The tie plate may be readily applied by slipping it on

the rail base in a manner to position the 50 hooks 3 in embracing relation with the edge of the inner flange of the base, by driving it on the base until the rib 2 is clear of the edge of the outer flange thereof, and by then swinging it into contact with the bottom side of the base. As the hooks 3 are tensioned during the application of the tie plate, they constantly exert a downwardly directed pressure on the rail base, and as the result the rail will be positively held 60 against creeping in both directions. As the portion 1^a of the tie plate 1 which is located outwardly beyond the rib 2, is longer than that portion 1^b thereof which is located between and extends upwardly beyond the 65 jaws 3, the tie plate has a greater bearing surface on the outer than on the inner side of the rail, and in view thereof will tend to camber the rail inwardly. With the rail in this position the friction and wear thereon is reduced to the minimum.

The tie plate is a one-piece structure, may be readily applied under full ballasted track, does not have to be removed from the rail when making tie renewals, and reduces the 75 wear on the tie to the minimum. As the tie plate is held snugly in contact with the rail base by the jaws 3, it will not rattle during the passage of a train over the rail.

I desire to have it understood that the device shown is merely illustrative, and that such changes may be made when desired as are within the scope of the invention as claimed.

What is claimed is:

A tie plate having a rib located inwardly beyond one side edge thereof, relatively spaced resilient jaws located at the corners and inwardly beyond the other side edge thereof, that portion of the tie plate located outwardly beyond the rib being greater in length than that portion located outwardly beyond the jaws, and said jaws being located at the ends of said latter portion and having upwardly curved inner terminals.

In testimony whereof I affix my signature.

WILLIAM P. HESTERLY.
